UNITED STATES PATENT OFFICE

2,268,021

STAIR CUSHION

Samuel Dominus, Brooklyn, N. Y.

Application June 7, 1940, Serial No. 339,350

2 Claims. (Cl. 154—56)

My invention relates to improvements in stair cushions, and it consists in the novel features which are hereinafter described.

One of the objects of my invention is to reinforce the backing of the carpet covering of a stair cushion at the points of stress thereon near the metal frame, whereby to prevent the unravelling of the backing of the said carpet covering near the said metal frame of the stair cushion.

Another object of my invention is to protect from abrasion the stitching of the carpet covering of the stair cushion to the cardboard base thereof, which is hereinafter described.

A further object of my invention is to reinforce the backing of the carpet covering of a stair cushion opposite the points of wear on the top of the said carpet covering by means of a sheet of lining, which is hereinafter described.

Another object of my invention is to reduce the stress on the threads of the stitching of the said covering to the said base by transferring the stress or part thereof to the said lining, which is packed tightly into the metal frame with the said covering and the said base thereof.

Another object of my invention is to make possible the use of loosely woven carpet for stair cushion coverings; heretofore only relatively closely woven carpet could be used for that purpose.

A still other object of my invention is to protect the edges of the cardboard base and to interpose a layer of fabric or other packing between the said cardboard base with the threads of the said stitching thereon and the metal frame.

A further object of my invention is to make my above improved stair cushion compact, simple, durable and inexpensive.

Other objects and advantages will hereinafter appear.

I attain these objects by the stair cushion illustrated in the accompanying drawing or by any mechanical equivalent or obvious modification of the same.

In the drawing Fig. 1 is a view in end elevation of the tread and riser of my improved stair cushion, which are shown in their relative positions.

Fig. 2 is a plan view of the same; and Fig. 3 is a front view thereof, showing the positions of the tread and riser with relation to each other.

Fig. 4 is a fragmentary view of the tread of my improved stair cushion, in section on the line 4—4 of Fig. 2, drawn to a larger scale than Figs. 1, 2 and 3; and

Fig. 5 is a fragmentary sectional view of the riser of my improved stair cushion on the line

5—5 of Fig. 3, also drawn to a larger scale than Figs. 1, 2 and 3.

Similar numerals refer to similar parts throughout the several views.

5 The tread 10 of my improved stair cushion is shown in Fig. 4 as comprising a carpet top covering 11—12 having thereon a fabric backing 11 and a nap or pile 12; a base 13 of cardboard or any other suitable material forms the bottom of the tread of my stair cushion.

A reinforcing lining 14 of canvas or any other suitable material is cemented on or otherwise secured to the backing 11 of the top covering 11—12; the lining 14 extends beyond the front and rear edges of the top covering 11—12; and the extension 15 thereof is folded over the front and rear edges of the base 13, thereby forming an assembly 21, after the base 13 has been secured to the front and rear edges of the top covering 11—12 by means of zig-zag stitches, as shown in dotted lines at 20 in Fig. 2.

The extension 15 is preferably not stitched to the base 13.

The space between the top covering 11—12 and the lining 14 thereon and the base 13 is shown in Fig. 4 as stuffed with resilient pads 16, 17 and 18, which may be made of felt or any other suitable material; and the edges of the assembly 21 are encompassed by a metal frame 19 which is secured thereto by folding the metal blank of the said frame 19 over the said assembly 21 and pressing it thereunto.

The lateral edges of the top covering 11—12, with the lining 14 thereon, and the base 13 are also secured to each other by stitching before the metal blank of the frame 19 is folded thereover.

The lining 14, instead of being cemented to the backing 11 of the top covering 11—12, may also be secured thereto by sewing, or it may be vulcanized thereto or woven thereinto; the lining 14 may also be of any flexible material, such as rubber or any fabric other than canvas.

By cementing or vulcanizing the lining 14 to the backing 11 of the top covering 11—12 or by weaving the lining 14 into the backing 11 of the top covering 11—12, the lining 14 is thereby integrated with the backing 11 of the top covering 11—12; to wit; it becomes one piece with it.

50 The lining 14 and the backing 11 of the top covering 11—12 cannot slide or creep on each other, or have any relative motion whatsoever therebetween.

55 The lining 14 reinforces the covering 11—12 at the points of stress thereon, and prevents un-

ravelling of the backing 11 at the front and rear edges of the latter near the metal frame 19.

It will be understood that there is a relative motion or creeping between the frame 19 and the edges of the cushion which it encloses, particularly at the front and rear edges of the cushion when the latter is being trod upon; the cushion being reversible, the rear edge becomes the front edge after the cushion is reversed in position; the extension 15 reinforces these edges.

The extension 15 protects the edges of the base 13 and prevents the abrasion of the stitching 20 of the top covering 11-12 to the base 13 at the underside of the base 13.

The stitching 20 at the top of the top covering 12 is shielded by the nap of the carpet of which said covering is made and the stitching 20 is thereby protected against abrasion by the frame 19.

The lining 14 also reinforces the backing of the top covering 11-12 opposite the points of wear on the top of the said covering, and thereby prevents the formation of holes in the covering 11-12.

The reinforcement 14 takes up some of the stress which is exerted on the threads of the stitching 20.

The riser 30 of my improved stair cushion is shown in Fig. 5 as comprising a carpet front covering 22-23 having thereon a fabric backing 22 and a nap or pile 23; a base 24 of cardboard or any other suitable material forms the rear of the riser of my improved stair cushion; a reinforcing lining 26 of canvas or any other suitable material is cemented on or otherwise secured to the backing 22 of the front covering 22-23; the lining 26 extends beyond the top edge of the front covering 22-23, and the extension 25 is bent over the upper edge of the base 24 after the latter is stitched to the upper edge of the front covering 22-23 by means of zig-zag stitches, as shown in dotted lines at 20 in Fig. 3, thereby forming an assembly 31.

The extension 25 is preferably not stitched to the base 24.

The edges of the assembly 31 are encompassed by a metal frame 29 which is secured thereto by folding the metal blank of the said frame 29 over the said assembly 31 and pressing it thereunto.

The lateral edges of the covering 22-23 with the lining 26 thereon and the base 24 are also secured to each other by stitching before the frame 29 is folded thereover.

The lining 26 instead of being cemented to the backing 23 of the front covering 22-23, may also be secured thereto by sewing or it may be vulcanized thereto or woven thereinto; the lining 26 may also be of any flexible material other than canvas.

The lining 26 reinforces the front covering 22-23 at the points of stress thereon and prevents unravelling of the backing 22 at the upper edge of the latter near the metal frame 29.

Other advantages of the lining 26 and the extension 25 thereof with relation to the riser 30 are similar to the advantages of the lining 14 and the extension 15 thereof with relation to the tread 10 of my improved stair cushion.

A portion only of the lining 14 and the lining 26 may be used, if desired.

Other variations are possible, and parts of my invention may be used without other parts.

I do not therefore restrict myself to the details as shown in the drawing.

Whenever in the claims hereinafter the term integrated with is used it is meant to include the terms of cemented to, vulcanized to, and woven into.

I claim as my invention and desire to secure by Letters Patent:

1. In a stair cushion a carpet top covering and a base stitched thereto at the edges thereof, a metal frame encompassing the edges of the cushion and pressed thereunto, said covering having thereon a fabric backing, a lining of flexible material secured to said backing and an extension on said lining folded over the front edge of the base, with the covering stitched thereto, interiorly of said frame and exteriorly of the stitching, thereby protecting the stitching at the underside of the base from abrasion by the frame.

2. In a stair cushion a carpet top covering and a base stitched thereto at the edges thereof, a metal frame encompassing the edges of the cushion and pressed thereunto, said covering having thereon a fabric backing, a lining of flexible material secured to said backing and an extension on said lining folded over each of the front and rear edges of the base, with the covering stitched thereto, interiorly of said frame and exteriorly of the stitching, thereby protecting the stitching at the underside of the base from abrasion by the frame.

SAMUEL DOMINUS.
